UNITED STATES PATENT OFFICE.

HIRAM E. GIDEONS, OF BAY MINETTE, ALABAMA.

BOLT-HEADING TOOL.

1,031,782.

Specification of Letters Patent. Patented July 9, 1912.

Application filed July 1, 1911. Serial No. 636,531.

To all whom it may concern:

Be it known that I, HIRAM E. GIDEONS, a citizen of the United States, residing at Bay Minette, in the county of Baldwin, 5 State of Alabama, have invented certain new and useful Improvements in Bolt-Heading Tools; and I do hereby declare the following to be a full, clear, and exact description of the invention, such as will 10 enable others skilled in the art to which it appertains to make and use the same.

This invention relates to bolt heading tools.

The object of the invention resides in the 15 provision of a tool of the character named which may be utilized with ease and facility in heading bolts of different types and is especially useful in those localities where larger bolt heading machinery is not accessible and where the time in which the heading 20 of the bolt must be completed is limited.

A further object of the invention resides in the provision of a tool of the character named which will be simple in construction, 25 durable, effective in reaching the end for which it is designed, and which may also serve the purpose of a bending tool through the aid of which rods or other stock may be easily bent at the proper angle.

With the above and other objects in view, 30 the invention consists in the details of construction and in the arrangement and combination of parts to be hereinafter more fully described and particularly pointed out 35 in the appended claim.

In describing the invention in detail, reference will be had to the accompanying drawings, wherein like characters of reference denote corresponding parts in the several views, and in which—

Figure 1 is a side elevation of the tool showing same secured to an ordinary blacksmith anvil, the latter being broken away to better disclose the connection between the 45 anvil and tool, Fig. 2, an end view of the tool removed from the anvil, Fig. 3, a section on the line 3—3 of Fig. 2, Fig. 4, a section on the line 4—4 of Fig. 3, Fig. 5, a detail perspective view of the movable jaw of the tool, with the die removed from its seat in said jaw, Fig. 6, a detail perspective view of the fixed jaw of the tool with the die removed from its seat therein, and Fig. 7, a detail perspective view of one of the dies 50 adapted for association with the movable jaw of the tool.

Referring to the drawings, A indicates an ordinary blacksmith anvil which is adapted to form a support for the tool during the use of the latter.

The tool proper comprises a base 10 provided with a depending squared stem 11 adapted to removably seat in the squared opening 12 of the anvil A so as to constitute a detachable connection between the 60 tool and the anvil. The base 10 is provided intermediately with a recess 13 in which is disposed a rib 14 rising from the rear wall of the recess and extending from end to end thereof. Formed at one end of the base 10 is an extension 15 the free end of which is forked to produce spaced ears 16 and 17 for a purpose that will presently appear. The base 10 and the various parts rigidly connected therewith constitute the fixed jaw of 70 the tool as will hereinafter appear.

The movable jaw of the tool is indicated at 18 and has one end extended to form an operating handle 19, while the other end thereof is extended and reduced to form a tongue 20 disposed between the ears 16 and 17 and pivotally connected to the latter by means of a pivot pin 21 whereby the movable jaw may be swung through the instrumentality of the handle 19 toward and 80 away from the fixed jaw when desired. The edge of the movable jaw 18 adjacent the fixed jaw or base 10 is provided with a recess 22 which is disposed in opposition to and mates with the recess 13 in the fixed 90 jaw when said movable jaw is moved into engagement with the fixed jaw. This recess 22 has disposed therein a rib 23 which rises from the rear wall of said recess and extends from end to end thereof in a manner corresponding to the rib 14 in the recess 13.

Removably mounted in the recesses 13 and 22 respectively are mating dies 24 and 25, the adjacent edges of which are provided 100 respectively with mating grooves 26 and 27 which are adapted to receive the bolt shank therein during the heading operation. Corresponding ends of these grooves are enlarged and squared as at 28 and 29 respectively to form a mold or socket to receive the heated metal during the formation of the head of the bolt. Each of the dies 24 and 25 have their remote edges provided with grooves 30 and 31 respectively adapted 105 to receive the ribs 14 and 23 respectively so as to effect an interlocking engagement be-

tween said dies and the fixed and movable jaws of the tool respectively. In order to prevent the removal of the die 25 from the recess 22 under the influence of gravity, there is pivoted on the movable jaw 18 a hook 32 adapted to detachably engage a laterally projecting pin 33 fixed on the die 25.

In use the movable jaw 18 is lifted away from the fixed jaw or base 10 and the heated rod of metal from which the bolt is to be formed is placed in the groove 26 of the die 24. When the metal is thus positioned the movable jaw 18 is pressed into engagement with the fixed jaw and the heated rod of metal will substantially fill the grooves 26 and 27. The end of the rod of metal adjacent the enlarged squared portions of the groove 26 and 27 is then hammered until it is caused to flow and completely fill the enlarged squared portions 28 and 29 and the metal thus forced into the squared portions 28 and 29 will constitute a proper head for the bolt.

It will of course be apparent that by changing the form of the dies 24 and 25 bolts with different shaped shanks and different shaped heads may be produced by

the same operation as that previously described.

The movable jaw 18 is guided into correct relation to the fixed jaw 10 by means of a stud 34 carried by the movable jaw 18 and which enters a recess 35 formed in the adjacent face of the fixed jaw.

What is claimed is:

A tool of the class described comprising a pair of pivotally connected co-operating jaws, said jaws having opposed recesses in their adjacent edges, ribs formed on the inner walls of said recesses respectively extending longitudinally of respective jaws and disposed intermediate the sides of the latter, a die mounted in each of said recesses and removably interlocking with said rib whereby said dies are held against lateral movement relatively to the jaws, and means for securing one of said dies against movement transversely of the plane of its supporting jaw relatively to the latter.

In testimony whereof, I affix my signature, in presence of two witnesses.
